US00D616541S

(12) **United States Design Patent**
Mason, Jr.

(10) **Patent No.:** **US D616,541 S**
(45) **Date of Patent:** ** *May 25, 2010

(54) **SANITARY TOWEL**

(75) Inventor: **Peter Charles Mason, Jr.**, Maineville, OH (US)

(73) Assignee: **The Procter & Gamble Company**, Cincinnati, OH (US)

(*) Notice: This patent is subject to a terminal disclaimer.

(**) Term: **14 Years**

(21) Appl. No.: **29/270,188**

(22) Filed: **Dec. 18, 2006**

(30) **Foreign Application Priority Data**

(57) **CLAIM**

The ornamental design for a sanitary towel, as shown and described.

DESCRIPTION

FIG. 1 is a top view of a sanitary towel; and,

FIG. 2 is a perspective view of the sanitary towel shown in FIG. 1.

The waves represented are exemplary.

The broken lines shown in the drawings are for illustrative purposes only; they indicate the boundaries of the claimed design and form no part of the claimed design.
